FOREIGN PATENT DOCUMENTS

GB 10159 A 0/1911

FIG. 1 is a top perspective view of an end hook for measuring tape according to a first embodiment;

FIG. 2 is a side elevation view thereof;

FIG. 3 is a front elevation view thereof;

FIG. 4 is a top plan view thereof;

FIG. 5 is a bottom plan view thereof;

FIG. 6 is a top perspective view of an end hook for measuring tape according to a second embodiment;

FIG. 7 is a side elevation view thereof;

FIG. 8 is a front elevation view thereof;

FIG. 9 is a top plan view thereof; and,

FIG. 10 is a bottom plan view thereof.

The broken line showing of a portion of the measuring tape is included for the purpose of illustrating non-claimed subject matter and forms no part of the claimed design.
